UNITED STATES PATENT OFFICE.

ROBERT CRANE, OF PHILADELPHIA, PENNSYLVANIA.

SYSTEM OF ACCOUNTING AND TAGGING.

No. 922,672.

Specification of Letters Patent.

Patented May 25, 1909.

Application filed March 22, 1906. Serial No. 307,329.

To all whom it may concern:

Be it known that I, ROBERT CRANE, a citizen of the United States, and a resident of the city of Philadelphia, State of Pennsylvania, have invented certain new and useful improvements in Systems of Accounting and Tagging, of which the following is a full, clear, and complete disclosure.

My invention relates to a system of accounting and tagging, and particularly to that class of such which comprehends the reproduction of certain entries or parts of entries to be used separately or away from leaves or books of account.

The object of my invention is to provide a system in which the entries made are reproduced either in whole or in part upon shipping or other tags.

A further object of my invention is to produce a device in which a leaf of account may be retained upon a flat surface in such a manner that certain entries thereon will be reproduced upon tags or the like, and with this object in view my invention consists in the details of construction and manner of operation set forth in the following description and accompanying drawing, like reference characters referring to corresponding parts.

The figure on the drawing represents a perspective view of my device.

In this view I have illustrated my account sheet 1, as a loose leaf to be bound in a sales book, and being suitably lined and ruled for entries relating to transactions in the sale and delivery of goods. The leaf or page 1 is divided into columns 2 and 3, the right-hand column 3 being intended for entries of names and addresses of persons to whom goods are to be delivered, the amount charged or to be collected, and such other entries as may be desired. All of these entries are to be reproduced on tags, in a manner which will be hereinafter described.

The left-hand column 2 is intended for the regular sales book entries, including the name of the goods, the amount, whether charged or paid, etc., in the usual manner of entering up sales in accounting. Thus,

the account sheet not only discloses the regular sales account but an exact duplicate of the entries on the tag, which is to be attached to the goods sold. In order to reproduce these latter entries upon the tags, it is necessary to place that part of the leaf

represented by the column 3 over a strip of tags, a sheet of carbon paper being placed between the account leaf and the tags. The entries made in column 3 will then be reproduced on the tags, after which the leaf 60 may be fastened in a suitable binder.

In order to obtain a flat surface suitable to write upon and to maintain the leaf and tags in proper relative relation, I utilize such a device as shown in the drawing, 65 which consists of a flat support 20, having attached to its upper surface the bar 4 of the spring clamping device, which will be hereinafter described, and the lug 5, both of which form abutments for the upper and one 70 of the side edges of the leaf 1. These abutments serve to fix the exact position of the leaf when it is first placed upon the support, after which it is detachably secured in position by the clamp member 6, attached to the 75 hereinbefore mentioned clamping device. On the upper side of the board and arranged under the column 2 of the leaf is a sheet 7, made of pasteboard or other like material. This sheet is pasted or otherwise 80 fastened to the support 20, and its right-hand edge forms an abutment for the tags 8, when these tags, which are attached together in any suitable manner, are slipped in under the leaf. The said abutment thus serves to 85 fix the position of the tags relative to the column 3 of the leaf 1. The pasteboard sheet also serves as a backing for the leaf when entries are made thereon.

I may use any means for holding the leaf 90 1 to the support 20, but preferably employ one which offers the least obstruction to the hand when making the entries. The one illustrated in the drawing consists of a base bar 4 screwed to the left-hand side of the 95 support 20, having projecting upwardly therefrom the alined apertured lugs 10, in which is rotatably journaled the rod 11. The spiral springs 12—12' encircle the rod 100 between the two pair of end lugs respectively, each of said springs having one extremity fastened to said rod and the other extremity fastened to one of the adjacent lugs.

Adjustably attached to the rod 11 are the 105 arms 13, 14 and 15, which support the clamp member 6, being fastened to the same by screws or in any other suitable manner. The arms 13 and 15 are held rigid with the rod 11 by the screws 16 and 17 respectively. The 110

arm 14 is fastened to the shaft by a split collar, the lower section 18 being fastened to the upper section by screws 18'.

Integral with and projecting outwardly from the arm 14 is the handle or lever 19, which is used to rotate the rod against the resistance of the springs, to raise the clamp member clear of the leaf for the purpose of insertion or removal of the latter. This clamp member may be serrated, as shown, for the purpose of more securely retaining the leaf in position, and when in its normal position, bearing down against the support, has its contact surface coinciding with the middle line of the page, which divides the latter into columns 2 and 3. This contact surface is so arranged with reference to the support that, should the leaf be removed, the said edge normally bears against the extreme right-hand portion of the sheet 7. By virtue of this manner of retaining the leaf in position, the right side thereof, having thereon the column 3, may be turned upwardly on the clamp member 6, in the same manner as if it were a page of a book bound by said clamp member, thus enabling the tags to be inserted, together with the carbon paper, and also to give a view of the tags at different times during the making of the entries.

While the spring clamp above described is my preferred form, and has advantages due to its peculiar construction, I wish it distinctly understood that any means for holding the leaf in position are included within the scope of my invention.

I have described a leaf adapted to be fastened in a sales book, but a leaf adapted for any other account book, which is intended to have a part of its entries reproduced on tags, may be utilized.

I have described my invention as applied to the reproduction of entries on a strip of tags, but it is obvious that one or more tags may be used as desired, and further, whenever I have used the expression "tag" or "tags" I mean to include thereby any labels of a like nature; that is, any sheet or sheets on which it is desired to reproduce entries.

Although it would seem most convenient to have the column under which the tags are placed at the right of the support, yet the clamping device and the other parts may be rearranged to have this part of the leaf in any other location on the support.

My device, on account of its convenient size, may be readily carried around by the person making the entries, or may be rested upon the knee or on any other convenient support, to furnish a flat writing surface.

Having now described my invention, what I desire to claim and secure by Letters Patent of the United States is:

1. The combination with a support, having a face surface provided with portions

arranged in different planes and having a shoulder between said portions extending longitudinally of said support, of a clamp member yieldingly connected to said support and having an edge substantially in alignment with said shoulder.

2. The combination with layers of paper, of a support for the same and a clamp member connected to said support and having an edge extending longitudinally of said support for holding said layers in position, said support being provided with a shoulder substantially in alignment with the edge of said clamp member, said layers being more numerous upon one side than on the other and forming a shoulder resting against the shoulder of said support.

3. The combination with a support having a face surface provided with portions arranged in different planes and having a shoulder between said portions, of a tag resting upon said support and against said shoulder, a sheet of transfer material over said tag, an account leaf over said transfer sheet, and a clamp extending in alignment with said shoulder for holding said tag, said sheet and said leaf in position.

4. The combination with a support provided with a shoulder upon its upper surface, of a tag upon said support resting against said shoulder, a transfer sheet upon said tag, a leaf of writing material upon said transfer sheet, and means for securing said leaf, sheet and tag to said support.

5. The combination with a support provided with a shoulder upon its upper surface, of a tag upon said support resting against said shoulder, a transfer sheet upon said tag and near said shoulder, a leaf of writing material upon said transfer sheet, and a clamp in alignment with said shoulder.

6. The combination with a support, of a sheet of backing material fixed upon one portion of said support and forming a shoulder therewith, a tag resting upon said support and against said shoulder, a transfer sheet upon said tag, and a leaf of writing material upon said transfer sheet and extending over said backing sheet.

7. The combination with an account leaf ruled in columns, of a support upon which said leaf rests, a tag covered with a sheet of copying material interposed between one of said columns and said support, and means for detachably securing said leaf and said tag to said support.

8. The combination with an account leaf ruled in columns, of a support upon which said leaf rests, a tag covered with a sheet of copying material interposed between one of said columns and said support, and a yielding clamp member for detachably securing said leaf and said tag to said support.

9. The combination with a support, of a sheet of backing material arranged upon

one side of said support and having an edge forming an abutment, a tag upon said support and against said abutment, a sheet of copying material upon said tag, and a leaf 5 of writing material over said copying sheet and said backing sheet.

10. The combination with a support, of a sheet of backing material arranged upon one side of said support and having an edge 10 forming an abutment, a tag upon said support and against said abutment, a sheet of copying material upon said tag, a leaf of writing material over said copying sheet and said backing sheet, and means for de- 15 tachably holding said leaf in position.

11. The combination with a support, of a sheet of backing material arranged upon one side of said support and having an edge forming an abutment, a tag upon said 20 support and against said abutment, a sheet of copying material upon said tag, a leaf of writing material over said copying sheet and said backing sheet, and a clamp having a member extending across said leaf for de- 25 tachably holding the same in position.

12. The combination with a support, of a sheet of backing material arranged upon one side of said support and having an edge forming an abutment, a tag upon said 30 support and against said abutment, a sheet of copying material upon said tag, a leaf of writing material over said copying sheet and said backing sheet, and means on said support to position said leaf relative to said 35 tag.

13. The combination with a support, of a sheet of backing material arranged upon a portion of the face side thereof, the said 40 sheet having one of its edges forming an abutment, a tag resting upon said support and against said abutment, copying material upon said tag, a leaf of writing material over said copying material and extending over said backing sheet, and abutments on 45 said support to position the said leaf relative to the said tag.

14. The combination with a support, of a sheet of backing material arranged upon a portion of the face side thereof, the said 50 sheet having one of its edges forming an abutment, a tag resting upon said support and against said abutment, copying material upon said tag, a leaf of writing material over said copying material and extending 55 over said backing sheet, abutments on said support to position the said leaf relative to the said tag, and a clamp for holding the said leaf in position.

15. The combination with a support, of a sheet of backing material arranged upon a portion of the face side thereof, the said 60 sheet having one of its edges forming an abutment, a tag resting upon said support and against said abutment, copying material 65 upon said tag, a leaf of writing material

upon said copying material and extending over said backing sheet, abutments on said support to position the said leaf relative to the said tag, and a clamp for holding the said leaf in position, said clamp having an 70 edge substantially in alignment with one of said abutments.

16. The combination with a support, of a backing sheet fixed upon one side thereof and covering a portion of said side, one edge 75 of said sheet forming an abutment, a tag upon said support and resting against said abutment, a sheet of copying material over said tag, a sheet of writing material extending over said copying sheet and over said 80 backing sheet, and abutments on said support for the edges of said leaf to determine the position of said leaf relative to the tag.

17. The combination with an account leaf, 85 of a support on which said leaf rests, a tag covered with copying material arranged beneath a portion of said leaf upon one side thereof, a shoulder upon said support beneath said sheet to position said tag and said copying material, a clamp member yieldingly secured to said support and having an edge substantially in alignment with said shoulder to hold said leaf, tag and sheet in position.

18. The combination with a support having a face surface provided with portions arranged in different planes, and having a shoulder between said portions, of a clamp member yieldingly connected to said support and having an edge substantially in 90 alignment with said shoulder.

19. The combination with a support having a face surface provided with portions arranged in different planes, and having a shoulder between said portions, of a clamp 105 member connected to said support and having an edge substantially in alignment with said shoulder.

20. The combination with a support having a face surface provided with portions arranged in different planes, and having a shoulder between said portions extending longitudinally of the support and intermediate of the side edges thereof, of abutments 110 adjacent the end and side edges of said support for positioning a sheet of writing material thereon.

21. The combination with a support of an abutment extending upon one side thereof, a second abutment between the said first abutment and the opposite side of the support to hold layers of paper in spaced relationship upon the same sides of said abutments respectively and means to clamp said 120 layers in fixed position.

22. The combination with a support having an abutment extending longitudinally thereof and adjacent one of the side edges of said support, of a second abutment parallel to said first abutment and substantially 130

midway between said first abutment and the opposite edge of said support, and a clamp having an edge parallel to said abutments and adjacent said second abutment.

5 23. The combination with a support having an abutment adjacent one of the side edges thereof and a second abutment parallel to said first mentioned abutment and between said first mentioned abutment and the 10 opposite side edge of said support, of an abutment adjacent one of the under edges of the said support for positioning layers of writing material upon said support, and means for holding said layers in fixed 15 position.

24. The combination with a substantially rectangular support having an abutment extending parallel and adjacent to one of the side edges thereof and a second abutment 20 parallel to said first abutment and between

said first abutment and the opposite edge of said support, an abutment extending parallel to and adjacent one of the end edges of said support and a clamp connected to said support and having an edge substantially in alinement with the said second mentioned abutment. 25

25. The combination with a support having a face surface divided into two portions having an abutment between said portions, 30 of a clamp member connected to said support and having an edge substantially in alinement with said abutment.

In witness whereof, I have hereunto set my hand this 20th day of March, A. D., 1906. 35

ROBERT CRANE.

Witnesses:

ALEXANDER PARK,
ALSTON B. MOULTON.

It is hereby certified that in Letters Patent No. 922,672, granted May 25, 1909, upon the application of Robert Crane, of Philadelphia, Pennsylvania, for an improvement in "Systems of Accounting and Tagging," an error appears in the printed specification requiring correction, as follows: In line 11, page 4, the word "under" should read *end*; and that the said Letters Patent should be read with this correction therein that the same may conform to the record of the case in the Patent Office.

Signed and sealed this 15th day of June, A. D., 1909.

[SEAL.]

C. C. BILLINGS,
Acting Commissioner of Patents.
